GESELLSCHAFT, OF ESSEN-ON-THE-RUHR, GERMANY.

IRON PILING.

1,079,814.

Specification of Letters Patent.

Patented Nov. 25, 1913.

Application filed September 28, 1912. Serial No. 722,863.

To all whom it may concern:

Be it known that I, FRANZ WIEDER, residing at Bliersheim, Germany, a subject of the Emperor of Germany, have invented a 5 certain new and useful Improvement in Iron Pilings, of which the following is a specification.

The subject matter of the present invention is an iron piling combining necessary 10 strength with simplicity in manufacture and which by joining a piling to the next one, will produce a very sure joint.

In the drawing is illustrated Figure 1 a cross section of a piling wall, in which the 15 piles are formed in accordance with this invention; and Fig. 2 a cross section of a single pile.

In order to produce an iron pile, a bar of cross shaped cross section is first rolled out 20 in the usual manner, having four shanks the two neighboring shanks of which A, being of the same length and slightly longer than the two other shanks A¹. The two longer shanks A will thereupon be finished-rolled 25 in such a manner that their free ends will be turned inward and bent so that hook shaped flanges a² will be produced. As shown in the drawing the measurement has been so selected that the distance measured 30 between the inside of the flanges a² and the other shank A, also provided with a flange a² is approximately equal to the length of the shorter shank A¹ with the addition of the thickness of the wall. The iron piles 35 may be therefore joined together, each iron pile with its two flanges a² inclosing the two shorter shanks A¹ of the neighboring pile, forming a secure guide, as will be evident from the drawing.

40 I claim:

1. A cross shaped pile having two pairs of longitudinal blades, one pair of which forming a female member and the other pair a male member.

45 2. A cross shaped pile having two pairs of longitudinal blades, one pair of which forming a female member and the other pair a male member; said pairs of blades being oppositely disposed to each other on 50 each side of a central plane and their blades forming continuations of each other.

3. A cross shaped pile having two pairs of longitudinal blades, one pair of which forming a female member and the other

pair a male member; the female pair of 55 blades having inwardly bent flanges.

4. A cross shaped pile having two pairs of longitudinal blades, one pair of which forming a female member and the other pair a male member; the female pair of 60 blades having inwardly bent flanges; said pairs of blades being oppositely disposed to each other on each side of a central plane and their blades forming continuations of each other. 65

5. A cross shaped pile having two longer and two shorter longitudinal blades, the two longer blades being provided with flanges bent toward each other.

6. A cross shaped pile having two longer 70 and two shorter longitudinal blades, the two longer blades being provided with flanges bent toward each other at approximately right angles.

7. A cross shaped pile having two longer 75 and two shorter longitudinal blades, the two longer blades being provided with flanges bent toward each other, the two longer blades situated to one side and the two shorter blades to the other side of the pile, 80 whereby said longer blades are adapted to securely engage the shorter blades of the adjoining pile when built up to form a wall.

8. A cross shaped pile having two longer 85 and two shorter longitudinal blades, the two longer blades being provided with flanges bent toward each other at approximately right angles, the two longer blades situated to one side and the two shorter blades to the other side of the pile, whereby said longer 90 blades are adapted to securely engage the shorter blades of the adjoining pile when built up to form a wall.

9. Iron piling comprising a series of interengaging individual piles, of identical 95 cruci-form transverse section, each pile having two pairs of longitudinal blades, one pair of which forming a female member and the other pair a male member.

10. Iron piling comprising a series of interengaging individual piles, of identical 100 cruci-form transverse section, each pile having two pairs of longitudinal blades, one pair of which forming a female member and the other pair a male member; the female 105 pair of blades having inwardly bent flanges.

11. Iron piling comprising a series of interengaging individual piles, of identical

- cruci-form transverse section, each pile having two pairs of longitudinal blades, one pair of which forming a female member and the other pair a male member; the female
- 5 pair of blades having inwardly bent flanges; said pairs of blades being oppositely disposed to each other on each side of a central plane and their blades forming continuations of each other.
- 10 12. Iron piling comprising a series of interengaging individual piles, of identical cruci-form transverse section, each pile having two pairs of longitudinal blades, one pair of which forming a female member and
- 15 the other pair a male member; the female pair of blades having inwardly bent flanges; said pairs of blades being oppositely disposed to each other on each side of a central plane and their blades forming continuations of each other; the female mem-

bers of one individual pile engaging the male members of the nearest individual pile, thereby securely locking the piles to each other in order to form a continuous wall.

13. Iron piling comprising a series of 25 similar members, each essentially cross shaped in transverse section, thereby providing on its opposite sides, pairs of symmetrically related blades; the blades on one side of each member being deflected to provide an interlocking conformation with respect to the blades on the opposite side.

The foregoing specification signed at Barmen, Germany, this 9th day of September, 1912.

FRANZ WIEDER. [L.S.]

In presence of—

ALBERT NUFER,
GUSTAVO NAVARRETE.
